United States Patent Office

Des. 211,615

Patented July 2, 1968

211,615

LABEL APPLYING DEVICE

Frederick N. Stephens, Leawood, Kans., assignor to
Stephens Industries, Inc., Kansas City, Mo., a cor-
poration of Missouri

Filed Oct. 9, 1967, Ser. No. 8,910

Term of patent 14 years

(Cl. D74—1)

Fig. 1.

Fig. 2.

Fig. 3.

Fig. 4.

Fig. 5.

Fig. 6.

FIG. 1 is a side elevational view of a label applying device embodying my design;

FIG. 2 is a perspective view of same showing the side opposite that seen in FIG. 1;

FIG. 3 is a top plan view of FIG. 1;

FIG. 4 is a bottom plan view of same;

FIG. 5 is an end elevational view of same taken from the left hand end of FIG. 1; and

FIG. 6 is an end elevational view of same taken from the right hand end of FIG. 1.

I claim:

The ornamental design for a label applying device, as shown and described.
